SPLIT RING CLAMP

Martin Hoffinger, 382 Garfield Ave.,
West Hempstead, N.Y.
Filed June 28, 1961, Ser. No. 120,401
1 Claim. (Cl. 24—271)

This invention relates particularly to closure locks; more specifically it presents a split ring seal for a drum or the like; and more particularly it describes an adjustable lever-type clamping ring.

There are many well known split ring clamping devices in the prior art. Usually such devices include any one of several forms of lever mechanisms to fasten the split clamping rings and thereby retain a closure member securely on a container.

All of the prior art devices, however, suffer from a common defect. After some period of use, the gasket between the closure and the container will compress the pivot connections on the lever mechanism, and other members wear or become otherwise loose. Thus, after a period of time, the split clamping ring will fail to lock the closure to the container with sufficient tightness. This necessitates the replacement of the gasket between the closure and the container or the reworking or disposal of the ring.

It is a cardinal object of this invention, therefore, to provide an improved adjustable split clamping ring for retaining a closure member on a container.

It is another primary object hereof to set forth a device as above described that will be inexpensive, simple to manufacture and have relatively few working parts.

Another object and accomplishment hereof is to describe a split clamping ring that is designed for complete constriction over a container and closure, even after prolonged use, and compression of the gasket.

A further object hereof is to set forth a more durable closure clamp.

Still another object is to provide a split ring of the character described which may be readily assembled and installed.

With these objects in view, the invention consists of the novel features of construction and arrangement of parts which will appear in the following specification and recited in the appended claim, reference being had to the accompanying drawings in which the same reference numerals indicate the same parts throughout the various figures and in which:

FIG. 1 is a plan view of a portion of a split ring clamping device constructed according to this invention with a portion of the container shown in section and with the parts in their closed or clamped position.

FIG. 2 is a view corresponding to FIG. 1 but illustrating the parts in their open or non-locking position.

FIG. 3 is a view taken substantially along line 3—3 of FIG. 2 illustrating the locking adapter.

FIG. 4 is a view taken substantially along line 4—4 of FIG. 3.

Referring to the drawings which illustrate what may be for some purposes a preferred embodiment of the invention, there is illustrated a split ring clamping device 10.

It will be noted that many of the details of the construction and operation of the split ring clamp are not shown in detail in that it is of generally conventional construction and will form no part of the instant invention. Sufficient to say, however, that it will be of cylindrical form and will be channel shaped in order to engage and thereby lock the closure to a container 11, with a gasket therebetween. As is generally known, the tighter the ring 10 is drawn, the better will be the con-

2

nexion between the closure and the container 11, within certain limits.

As is general, the gasket between the closure and the container will compress after a period of use and therefore the ring 10 will have to be drawn tighter to insure a perfect seal.

As illustrated, the ring 10 will generally have a lever locking device. The locking device will consist essentially of a lever 12 and a link 14. The said link 14 is pivotally connected to a point centrally located at the lever 12. The lever 12 is pivotally connected at one end to one side of the joint of the split clamping ring in such a manner that it may rotate in the same plane as the said ring 10. The pivotal connections may be by rivets or pins 15 and 16 loosely extending through the parts. It will generally be preferable for the pins or rivets 15 and 16 to have a certain minimum amount of clearance to insure free rotation.

The outward end of the link 14 is adjustably connected 20 to the ring 10 in a manner to be explained in detail hereinafter.

The outward end of the lever 12 may have an inwardly extending portion to lock on the opposite end of the split ring clamping device 10. The lever 12 is swung inwardly 25 against the ring 10 thereby locking the parts in position as demonstrated most clearly in FIG. 1.

With time, however, either due to the compression of the gasket between the closure of the container or due to wear of any of the parts, the split ring 10 may become 30 loose. This may be corrected easily by means of the adapter construction described immediately below.

Illustrated in FIGS. 3 and 4 of the drawings is one of the locking units 20 which will be constructed identically with the other locking unit 20a. The locking 35 adapter unit is formed preferably from a single strip of relatively rigid sheet material and formed into the illustrated shape. There will generally be a relatively long attaching surface 21 to secure the locking unit 20 to the split ring 10 or the link 14. In one form of the invention already constructed, the locking unit 20 was welded to the clamp 10 and spot welding points 22 were provided for ease of welding.

Referring again to the drawings, it will be seen that the illustrated embodiment of the device has side flanges 45 25 and overlying front flanges 26. This double front flange arrangement will insure the strength of the locking means at the point where strength is most necessary.

The front flanges 26 will each have a relatively central opening 28 which will be in line when the parts are in 50 their assembled position.

Referring again to FIGS. 1 and 2, it will be seen that the locking units 20 and 20a are fastened as by welding or the like to the outward end of the link 14 and to a point on the ring 10 disposed a short distance therefrom. 55 The parts are assembled in such position that the front flanges 26 of each of the locking units 20 and 20a are approximately parallel but spaced apart as may be seen at 30 in FIG. 1.

The operation of this invention then is as follows. The 60 split ring 10 is installed over the closure and the container 10 as seen in FIG. 2. The lever 12 is then urged to its locking position shown in FIG. 1. To insure the tightness of the parts and to prevent the spontaneous opening of the lever 12, a bolt 31, wire or the like, will be inserted through the openings 28 of the mating ends 65 of the locking units 20 and 20a. The bolt 31 will then be drawn tight as by a nut 32. It will be apparent that the tighter the torque on nut 32, the tighter the split ring 10 will be drawn on the closure and the container 11.

If, after several usages or after a prolonged period of time, any of the gaskets, joints, connections or pins 15

and 16 should wear or become otherwise loose. It will only be necessary to apply additional torque to the locking nut 32. This will draw the flanges 26 closer together and will maintain the tightness of the ring 10. This progressive shortening of the distance between the locking units 20 and 20a will effectively prevent the necessity for replacement of the gasket as the parts wear.

It will be apparent, therefore, that this invention accomplishes all of the objects hereinabove set forth. Most important, it presents effective and long lasting methods of sealing a closure on a container.

It will be obvious, of course, that the method of adjustment being somewhat flexible will eliminate fatigue and wear and tear of the critical portion of the ring and will therefore insure its long life.

While there are above disclosed but a limited number of embodiments of the structure and product of the invention herein presented, it is possible to produce still other embodiments without departing from the inventive concept herein disclosed, and it is desired, therefore, that only such limitations be opposed on the appended claim as are stated therein, or required by the prior art.

Having thus described my invention and illustrated its use, what I claim as new and desire to secure by Letters Patent is:

A split clamping ring closure, having a lever and a link, a first rotatable pin pivotally connecting one end of said link to a point centrally located of said lever, a second rotatable pin pivotally connecting one end of said

lever to one end of said split clamping ring, and a first locking adapter integrally fastened to said other end of said split ring, said first locking adapter having an apertured surface disposed perpendicularly to said split ring, and a second locking adapter integrally fastened to said link, said second locking adapter having an apertured surface extending perpendicularly of said link, and a straight bolt removably extending through said aperture of said surface of said second locking adapter whereby said first locking adapter and said second locking adapter may be urged toward each other by said bolt after said split clamping ring closure is closed, said first and said second locking adapters being each fabricated from a single strip of relatively rigid material, each of said locking adapters having side flanges and overlying double front flanges supported by said side flanges and comprising said apertured surface.
